(57) **ABSTRACT**

A new cherry tree variety suitable for use as rootstock.

6 Drawing Sheets

Specification includes a Sequence Listing.

1

Botanical designation: The present invention relates to a new *Prunus cerasus* L. x (*Prunus cerasus* L. x *Prunus canescens* Bois) cherry tree variety.

Variety denomination: The new plant has the varietal denomination 'Crawford'.

BACKGROUND OF THE INVENTION

This invention relates to a new and distinct variety cherry tree. It has as its (female) seed parent the variety known as 'Újfehértói Fürtös' (*Prunus cerasus*) (not patented) and as its pollen parent (male) the variety known as 'GiSelA® 6' U.S. Plant Pat. No. 8,954 (*Prunus cerasus* x *P. canescens*).

In the field of plant genetics, researchers conduct an extensive and continuing plant-breeding program including the organization and asexual reproduction of orchard trees, and of which plums, peaches, nectarines, apricots, cherries, almonds and interspecifics are exemplary. It was against this background of activities that the present variety of cherry tree was originated and asexually reproduced in our experimental orchard.

PRIOR VARIETIES

Among the existing varieties of cherry trees, which are known to us, and mentioned herein, 'Újfehértói Fürtös' (not patented), 'Hedelfingen' (not patented); 'Bing' (not pat-

ented); 'GiSelA® 5' U.S. Plant Pat. No. 9,644 and 'GiSelA® 6' U.S. Plant Pat. No. 8,954.

ORIGIN OF THE VARIETY

The present variety was developed from a first-generation cross between 'Újfehértói Fürtös', a Hungarian landrace sour cherry variety, and 'GiSelA® 6' made in 1998. Seeds resulting from the cross were germinated in East Lansing, Mich. and planted in Clarksville, Mich. in 2000. Seedlings were selected as candidate rootstocks based on overall plant health, virus tolerance (Prune Dwarf Virus, and *Prunus* Necrotic Ringspot Virus), and rooting percentage of soft-wood cuttings. Candidate rootstocks produced by asexual propagation were grafted with 'Hedelfingen' scion and planted in Clarksville, Mich. Further rootstock selection occurred on the basis of scion qualities to include precocity (early flowering and fruiting beginning the second year after planting) and reduced tree stature measured as trunk cross-sectional area. 'Crawford' was asexually reproduced through conventional softwood cutting methods, and grafted with 'Bing' scion. The 'Bing' trees grafted on the 'Crawford' rootstock were planted in Prosser, Wash. and evaluated for scion trunk cross-sectional area, tree height, growth habit, flowers per node, crop yield, cropping efficiency, and fruit weight, among other traits. Cherry tree 'Crawford' was selected from this trial.

ASEXUAL REPRODUCTION OF VARIETY

Asexual reproduction of the 'Crawford' cherry rootstock was achieved using the mother plant to obtain rooted liners using conventional softwood cutting procedures, and through meristem culture with commercial nurseries. Initially, liners were propagated from softwood cuttings in commercial greenhouses. A subset of these liners was used to establish a mother block in Clarksville, Mich. The remaining liners were sent to a nursery to make test trees of 'Crawford' that were budded with the scion 'Hedefingen'. The resulting trees were planted in a trial in Clarksville, Mich. A second set of liners was propagated from softwood cuttings in commercial greenhouses. These 'Crawford' liners were budded with 'Bing' scion to make trees for a trial in Prosser, Wash. The living tissues (i.e. leaves, stems, buds, flowers and fruits) of the original mother block plants were observed to be identical to secondary and tertiary vegetatively propagated plants.

STATEMENT OF STABILITY

Asexual propagation as described has demonstrated that the combination of traits that characterize this tree are fixed and remain true to type through at least two successive propagation cycles.

SUMMARY OF THE INVENTION

'Crawford' is particularly useful as a rootstock. The variety results in dwarf trees with significantly smaller canopy size than traditional non-dwarfing rootstocks and significantly smaller than trees on 'GiSelA® 6' rootstocks. When this variety is used as rootstock for sweet cherry, the fruit can be harvested without using ladders. When used as a rootstock for sour cherry the fruit can be harvested by an over the row harvester that can move continuously down the row instead of being harvested by a trunk shaking machine that harvests each tree individually. The variety of the invention also has favorable precocity, which results in a scion variety having flower buds and fruit beginning in years two and three rather than years five or six when traditional rootstocks are used. 'Crawford' was selected as a potential cherry rootstock on the basis of its scion trunk cross-sectional area, tree height, growth habit, flowers per node, crop yield, cropping efficiency, and fruit weight, among other traits, in two experimental field trials. Scion trees grafted onto this rootstock showed significant reduction in trunk cross sectional area compared to 'GiSelA® 6' and a trunk cross sectional area similar to 'GiSelA® 5'. 'Crawford' is suitable for standard nursery propagation practices for uniform liner production. 'Crawford' can be distinguished from its parents by the use of Simple Sequence Repeat DNA markers. With primer pair PceGA59, 'Crawford' is distinguished from its parent, 'GiSelA® 6' by the absence of the 226 base pair (bp) allele; and presence of the 194 bp allele. With the primer pair PruG4RS, 'Crawford' is distinguished from its parent, 'GiSelA® 6' by the presence of the 172 bp allele.

COMPARISON WITH PARENTS

The new cherry variety may be distinguished from its seed parent, 'Újfehértói Fürtös', a Hungarian landrace cherry variety in that 'Crawford' is not a sour cherry (*Prunus cerasus*) variety and 'Újfehértói Fürtös' is also not a dwarfing rootstock.

The new variety may be distinguished from its pollen parent, 'GiSelA® 6' by the following combination of characteristics: using the PceGA59 primer pair—the absence of the 226 bp allele; and presence of the 194 bp allele; using the 10 PruG4RS primer pair—the presence of the 172 bp allele; anthocyanin coloration of apex; leaf blade length, shape, and ratio of length to width; nectary shape; and intensity of anthocyanin coloration of young leaf

COMPARISON WITH KNOWN RELATED CULTIVARS

The new cherry variety may be distinguished from known related cultivars, for example the cherry trees named 'Clare' and 'Lake', by a combination of several characteristics. First, using the PceGA59 primer pair, it is shown that 'Crawford' contains the 182 allele (which 'Clare' and 'Lake' lack), and that 'Crawford' lacks the 226 allele (which both 'Clare' and 'Lake' possess). Additionally, using the 15 20 PruG4RS primer pair, it is shown that 'Crawford' has both the 192 and 200 alleles, which are not found in either 'Clare' or 'Lake'. Other differences in DNA fingerprint data are shown in Table 2. 'Crawford' differs from both 'Clare' and 'Lake' in the presence of pubescence (upper third), leaf length, leaf width, the leaf lower surface texture/pubescence, the leaf petiole length and diameter, the flower inflorescence diameter, fruit shape, and others.

'Crawford' may also be distinguished from 'GiSelA® 6' by its ploidy. Crawford is believed to be a tetraploid, whereas 'GiSelA® 6' is believed to be triploid. Crawford is further distinguished from 'GiSelA® 6' in that, using the PceGA59 primer pair, 'Crawford' possesses the 194 allele, which 'GiSelA® 6' lacks, and using the PruG4RS primer pair, 'Crawford' possesses the 172 and 'GiSelA® 6' does not. Additionally, using the PceGA59 primer pair, it is known that 'GiSelA® 6' possesses the 226 allele, which 'Crawford' lacks.

BRIEF DESCRIPTION OF PHOTOGRAPHS

40 The accompanying photographs display flowers, leaves, and fruits from a self-rooted mother block tree at Clarksville, Mich. in 2005.

FIG. 1 is a photograph of the flowers of CRAWFORD;

FIG. 2 is a photograph of two leaves of CRAWFORD;

45 FIG. 3 is a photograph of five leaves of CRAWFORD with a ruler to show size;

FIG. 4 is a photograph of cherries from and a seed from CRAWFORD;

FIG. 5 is a photograph of the young tree of CRAWFORD;

FIG. 6 is a photograph of an older tree of CRAWFORD.

DESCRIPTION OF THE NEW VARIETY

55 The following is a detailed botanical description of the new variety of cherry tree, its flowers, foliage and fruit, as based on observations of various aged specimens grown near Clarksville, Mich. with color in accordance with The Royal Horticultural Society Colour Chart (R.H.S.), 2001 edition.

Measurement details

60 Flowers:

Inflorescence height.—Measured from where the flower cluster attaches to the branch to the most distal floral part.

Flower diameter.—Measured across the petals in mm.

Flower length.—Measured from the bottom of the pedicel to the most distal flower point (mm).

<i>Pedicel</i> .—The stem of an individual flower. It is measured from the attachment in the bud to the start of the perianth.	5	<i>Varieties with nectaries only</i> .—Leaf — predominant number of nectaries: two.
<i>Peduncle</i> .—A stalk supporting an inflorescence. In these selections, the cherry flowers within a flower bud all start at the same base and they the stalk separates into individual pedicels supporting each flower.	5	<i>Leaf</i> .—Position of nectaries: base of leaf blade.
<i>Anther color</i> .—Before the anther's dehisce, when they are still bright yellow and plump.	10	<i>Nectary color</i> .—Yellow-green.
<i>Anther length</i> .—Measured for the longest anther measured from the top of the perianth tube.	10	<i>Nectary shape</i> .—Reniform.
<i>Style</i> .—Measured above the swelled ovary.		<i>Leaf stipule frequency</i> .—Present.
Tree:		<i>Leaf stipule length (mm)</i> .—10.
<i>Height</i> .—Approx. 10 ft.	15	<i>Leaf stipule width (mm)</i> .—2.
<i>Diameter</i> .—Approx. 10 ft.	15	<i>Leaf stipule shape</i> .—Pointed.
<i>Vigor</i> .—Weak.		<i>Leaf stipule margin</i> .—Serrated.
<i>Branching habit</i> .—Spreading.		<i>Flowers</i> :
<i>Branching</i> .—Strong.		<i>Flowers per cluster</i> .—1 to 4.
<i>Hardiness</i> .—Cold Resistant.	20	<i>Fragrance</i> .—None.
<i>Scion compatibility confirmed</i> .—Bing, Montmorency.		<i>Bloom date (50%)</i> .—Apr. 29, 2016.
Stem (trunk):		<i>Inflorescence diameter (cm)</i> .—3.8.
<i>Texture</i> .—Rough.		<i>Flower diameter (mm)</i> .—24.
<i>Color</i> .—Grey brown 200A.		<i>Flower length (mm)</i> .—27.
One year old shoot:	25	<i>Petal number per flower</i> .—5.
<i>Thickness</i> .—Thin.		<i>Petal arrangement</i> .—Flat whorl.
<i>Length of internode (middle third of shoot-mean of 10)</i> .—3.2 cm (2.9-4.0).		<i>Petal length (mm)</i> .—13.
<i>Pubescence (upper third)</i> .—Present.		<i>Petal width (mm)</i> .—10.
<i>Number of lenticels per cm²</i> .—5.	30	<i>Petal shape</i> .—Oval/round.
<i>Anthocyanin coloration of apex</i> .—Very weak.		<i>Petal apex</i> .—Round.
<i>Position of vegetative bud in relation to shoot</i> .—		<i>Petal margin</i> .—Smooth.
Slightly held out.		<i>Petal texture</i> .—Smooth.
<i>Shape of apex of vegetative bud</i> .—Obtuse.		<i>Petal color when fully opened</i> .—Upper surface (R.H.S.): 155D.
<i>Branching</i> .—Medium.	35	<i>Petal color when fully opened</i> .—Lower surface (R.H.S.): 155D.
Leaves:		<i>Sepal number</i> .—5.
<i>Mature leaf arrangement</i> .—Alternate.		<i>Sepal length (mm)</i> .—6.
<i>Intensity of anthocyanin coloration of young leaf (during rapid growth)</i> .—Weak.		<i>Sepal width (mm)</i> .—4.
<i>Leaf blade shape</i> .—Obovate.		<i>Sepal shape</i> .—Triangle.
<i>Leaf blade:ratio length to width</i> .—1.9.	40	<i>Sepal apex</i> .—Pointed.
<i>Leaf length-blade only (cm)</i> .—9.0.		<i>Sepal margin</i> .—Serrated.
<i>Leaf width (cm)</i> .—4.6.		<i>Sepal texture</i> .—Smooth.
<i>Leaf blade angle of apex (excluding tip)</i> .—Acute.		<i>Sepal color upper (R.H.S.)</i> .—138B.
<i>Leaf blade shape of base</i> .—Obtuse.		<i>Sepal color lower (R.H.S.)</i> .—138B with some 59A.
<i>Leaf blade shape of apex (e.g., acute)</i> .—Acute	45	<i>Flower pedicel length (mm)</i> .—11.
<i>Leaf blade; incisions of margin</i> .—Crenate.		<i>Flower pedicel diameter (mm)</i> .—1.
<i>Leaf blade</i> .—Depth of incisions of margin: medium.		<i>Flower pedicel angle (degrees)</i> .—30.
<i>Leaf blade glossiness of upper side</i> .—Medium.		<i>Flower pedicel texture</i> .—Smooth.
<i>Leaf blade</i> .—Pubescence of lower side of apex: medium.	50	<i>Flower pedicel color (R.H.S.)</i> .—138B.
<i>Upper surface color (R.H.S.)</i> .—137B.		<i>Flower peduncle length (mm)</i> .—5.
<i>Leaf upper surface texture/pubescence</i> .—Smooth.		<i>Flower peduncle diameter (mm)</i> .—2.
<i>Leaf upper surface venation color (R.H.S.)</i> .—138A.		<i>Flower peduncle texture</i> .—Smooth.
<i>Leaf venation pattern</i> .—Pinnate.		<i>Flower peduncle color (R.H.S.)</i> .—138B.
<i>Lower surface color (R.H.S.)</i> .—137C.	55	<i>Pistils</i> .—Number of pistils per flower: 1.
<i>Leaf lower surface texture/pubescence</i> .—Medium pubescence.		<i>Pistil length (mm)</i> .—11.
<i>Leaf lower surface venation color (R.H.S.)</i> .—138C.		<i>Pistil color (R.H.S.)</i> .—149B.
<i>Petiole</i> .—Presence of pubescence of upper side: present.		<i>Style length (mm)</i> .—9.
<i>Petiole</i> .—Intensity of pubescence of upper side: medium.	60	<i>Style color (R.H.S.)</i> .—138C.
<i>Petiole</i> .—Depth of groove: shallow.		<i>Stigma shape</i> .—Round/indented.
<i>Leaf petiole length (mm)</i> .—14.		<i>Stigma color (R.H.S.)</i> .—138B.
<i>Leaf petiole diameter (mm)</i> .—1.4.		<i>Stamens</i> .—Number per flower: 26 to 28.
<i>Leaf petiole color (R.H.S.)</i> .—138B and 59A.	65	<i>Longest filament length (mm)</i> .—7.
<i>Leaf</i> .—Presence of nectaries: present.		<i>Stamen filament color (R.H.S.)</i> .—155D.
		<i>Longest anther length (mm)</i> .—9.
		<i>Anther color (R.H.S.)</i> .—20B.
		<i>Pollen color (R.H.S.)</i> .—17C.
		<i>Pollen amount</i> .—Moderate.
		<i>Fruit</i> :
		<i>Mature fruit shape</i> .—Cordate.
		<i>Mature fruit height (mm)</i> .—18.2.
		<i>Mature fruit width 1 (mm)</i> .—16.8.
		<i>Mature fruit width 2 (mm)</i> .—18.6.
		<i>Mature fruit ratio height/width 2</i> .—0.98.
		<i>Mature fruit weight (g)</i> .—4.0.
		<i>Mature fruit flesh taste</i> .—Sour.

Mature fruit skin color (R.H.S.).—187A.
Mature fruit flesh color (R.H.S.).—187D.
Stone color (R.H.S.).—164D.
Stone shape.—Elongate.
Stone number.—1.
Stone height (mm).—11.1.
Stone width 1 (mm).—9.0.
Stone width 2 (mm).—7.2.
Stone ratio height/width 2.—1.53.
Stone weight (g).—0.36.
Fruit stem length (mm).—29.

Market use: Rootstock.

SIMPLE SEQUENCE REPEAT (SSR) MATERIALS AND METHODS

The use of clonally propagated *Prunus* sp. rootstocks in cherry production is increasing as these rootstocks provide reduced tree size and precocity. DNA markers that differentiate rootstocks are an important tool to verify identity among these rootstocks during the vegetative propagation stage. The simple sequence repeat (SSR) marker PceGA59 was previously determined to uniquely distinguish the commercially available GiSelA® rootstocks (Struss et al. 2002).

A targeted approach was used to develop a second SSR that was capable of providing differentiation of the rootstock selections of the invention and others by the inventors. The approach used was based on the ability to obtain genome-wide SNP (Single Nucleotide Polymorphism) data using the Illumina Infinium® cherry SNP array (Peace et al. 2012). An analysis of genome-wide SNP data for the rootstocks resulted in the identification of a genomic region on linkage group 4 that was likely to differ among the MSU rootstocks.

Using the peach genome sequence, an SSR marker was designed to target this region. This SSR marker, termed PruG4RS, successfully differentiated the MSU rootstocks. The development of PruG4RS and its combined use with PceGA59 has successfully circumvented the limitations of each individual marker and proven effective for use as a “quality control” DNA diagnostic tool for the commercial GiSelA® rootstocks as well as the MSU breeding program rootstock selections.

SSR MARKERS USED

Fingerprinting was performed using two simple sequence repeat (SSR) markers: PceGA59 and PruG4RS. The forward and reverse primers sequences for these two SSR markers are as follows:

TABLE 1

Primer name	Primer sequence 5' → 3'
PceGA59_redesigned_F	TGAACCCCTCTACAAATTTC
PceGA59_redesigned_R	GACTGTAGAACCCAAAAGAACG
PruG4RS - F	TCAGAAAAGAAATTGCAACGGG
PruG4RS - R	CTT AGT GGT CTA GTC TGC ATG C

The first primer pair, PceGA59, was published in Struss et al. (2002). However, the primer sequence reflects the addition of GC clamps. Based on genetic data for the MSU cherry rootstocks we designed a second primer, PruG4RS (Andersen et al. 2015).

PLANT MATERIAL USED AND DNA EXTRACTION

Cherry DNA was extracted from young unfolded leaf blades using the procedure of Edge-Garza et al. (2014).

POLYMERASE CHAIN REACTION (PCR)

PCR amplification was performed for the two SSRs using the following conditions: 94° C. for 5 min followed by 9 cycles of 94° C. for 30 s, 60° C. for 45 s (-1° C. per cycle), 72° C. for 1 min and then 24 cycles of 94° C. for 30 s, 55° C. for 45 s, 72° C. for 1 min with an elongation step of 72° C. for 5 min.

GEL ELECTROPHORESIS AND FRAGMENT VISUALIZATION

The PCR products were visualized by electrophoresis on a 6% denaturing polyacrylamide gel in a 50 cm Sequi-Gen GT vertical sequencing apparatus (Bio-Rad Laboratories, Hercules, Calif.) for 2.5 hours at 70 watts with 1× TBE buffer. Following electrophoresis, the gels were stained with the Silver Sequence DNA Sequencing System (Promega Corporation, Madison, Wis.) and dried for 24 hours. DNA fragment sizes were scored visually using 10 and 50 base pair ladders (Invitrogen Corporation, Carlsbad, Calif.).
